UNITED STATES PATENT OFFICE

2,507,235

HYDRAULIC ATTACHMENT FOR STACKERS AND LOADERS

William V. Warren, Salina, Kans., assignor to
The Wyatt Manufacturing Co., Inc., Salina,
Kans.

Application April 19, 1948, Serial No. 21,802

4 Claims. (Cl. 214—140)

1

This invention relates to stackers and loaders, and is an improvement over the construction embodied in application Serial No. 623,067, filed October 18, 1945, now Patent No. 2,481,994 granted Sept. 13, 1949, to Raymond M. Ginder for Hay Stack and Loader and over Patent No. 2,228,796, dated January 14, 1941, issued to William V. Warren for Stackers.

An object of this invention is to provide as an attachment for a hay stacker and loader, a hydraulic operator for the sweep which can be attached to present stackers and loaders as a substitute for the winch type operator.

Another object of this invention is to provide an operator attachment of this kind which will provide a three-to-one ratio with the use of only a pair of single pulleys so that the necessary swinging movement may be obtained for the sweep.

A further object of this invention is to provide an operator attachment of this kind which includes a frame for securing to the base of the stacker and loader frame, a hydraulic cylinder fixed longitudinally of the frame with the side bars of the frame forming guides for the ram or plunger, there being an idler pulley on the ram and a second idler pulley depending below the frame.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a plan view of the base frame of a stacker and loader having mounted thereon a hydraulic sweep operator constructed according to an embodiment of this invention.

Figure 2 is a detailed side elevation, partly broken away of the stacker and loader showing the manner in which the operator for the sweep is secured to the base frame.

Figure 3 is a fragmentary plan view, partly in section, on an enlarged scale, of the hydraulic operator.

Figure 4 is a detailed side elevation partly in vertical section of the operator.

Figure 6 is a sectional view taken on the line

—6 of Figure 4.

2

Figure 7 is a fragmentary sectional view taken on the line 7—7 of Figure 4.

Figure 8 is a fragmentary sectional view taken on the line 8—8 of Figure 2.

5 Referring to the drawings, the numeral 10 designates generally the base frame for a stacker and loader which, as shown in Figure 1, is formed of a pair of rearwardly convergent side bars 11 connected together at their rear ends by a 10 plate 12 and their forward or divergent ends by means of a connecting bar or rail 13. The side members 11 are also secured to a shaft or axle housing 14 and wheels 15 are disposed at the outer ends of the axle housing 14. The side 15 members 11 also have extending therebetween an intermediate connecting bar 16 and a pair of forwardly convergent bracing bars 17 are connected between the intermediate portions of the side members 11 and the forward connecting bar

20 13. The stacker and loader includes a substantially inverted V-shaped supporting member 18 on the upper end of which a sweep structure 19 is rockably mounted. The sweep structure 19 is adapted 25 to be vertically adjusted by means of an adjusting cable 20 which is trained about an idler pulley 21 carried by the sweep structure 19 adjacent the rear end thereof. The sweep structure 19 is vertically adjusted by means of a hydraulic adjuster 30 justing or operating attachment which includes a frame 22 formed of a pair of angle bars 23 connected together at their rear ends by means of a connecting angle member 24. The frame bars 23 are also connected together forwardly of the rear 35 ends thereof by means of a plate 25. The forward portions of the bars 23 engage over the top of transverse bar 13 and are secured thereto by means of a pair of upstanding lug members 26 which are carried by an angle member 42 fixed by 40 bolts 43 to angle member 13. Frame members 23 have fixed thereto lugs 44, and lugs 26 are secured to lugs 44 by bolts 45. The frame bars 23 are disposed on a downward and rearward inclination as shown in Figures 2 and 4 and are secured at their rear portions to transverse member 16 by means of vertically disposed angle members 27. A hydraulic cylinder 28 is disposed between the frame bars 23 being fixed at its rear end on angle member 24 by means of a U-bolt 29. 45 The cylinder 28 is also fixed on the plate 25 by means of a U-bolt 30. The cylinder 28 has slideable therein a piston or ram 31 which has secured to its outer end a plate or head 32. A sheave block 33 embodying a single pulley 34 is secured to and 50 extends forwardly of plate 32 and cable 20 is

trained over pulley 34 and extends downwardly and rearwardly therefrom.

The connection plate 25 has dependingly secured thereto a second sheave 35 embodying a single pulley 36 and the cable 20 extends partly about pulley 36 and from this pulley extends forwardly and upwardly as indicated at 37. A round bar 38 is secured to the lower edge of plate 32, cable extension 37 engaging under the bar 38 and then extending upwardly and is secured to a 10 bolt 39 carried by the sheave block 33.

The frame bars 23 form a guide for the ram 31 and in the present instance the frame members 23 have one side thereof extending inwardly as indicated at 40. The plate or head 32 has extending laterally therefrom slide bearing 41 engaging beneath the horizontal slides 40 of the guide members 23 so that the ram 31 will be relieved of any upward strain caused by raising of the sweep structure 19 when the latter is loaded.

In the use and operation of this device the hydraulic attachment herein disclosed is designed as a substitute for the mechanical sweep operator which is used on stackers and loaders at present available. It will be understood that this hydraulic operator may also be incorporated in a new sweep structure. The frame structure 22 is secured within the base frame 10 being secured to forward transverse bar 23 on the upper side of this bar and secured to intermediate transverse bar 16 in depending relation with respect to this bar. The cylinder 28 is connected to a source of fluid pressure supply and when it is desired to raise the sweep, ram 31 is moved forwardly thereby increasing the length of the loop between the sheave assemblies 33 and 35. Due to the fact that sheave assembly 35 is carried by a fixed portion of the frame and sheave assembly 33 is movable and one end of the cable 20 is secured to the sheave assembly 33, there will be provided a three-to-one ratio so that the cylinder 28 and the ram 31 may be made of relatively short length.

I claim:

1. A sweep operator attachment for a stacker and loader having a base frame formed of side bars and transverse connecting bars, an upstanding support carried by said base frame, and a rockable sweep structure rockably mounted intermediate the height of said support; said attachment comprising a frame formed of a pair of parallel frame angle bars for disposing lengthwise of said base frame and at a forward and upward inclination relative to the latter, said angle bars being disposed with the horizontal flanges thereof uppermost and extending inwardly towards each other, means securing the forward portions of said pair of bars to a forward connecting bar, a cross bar fixed to the rear portions of said pair of bars, means securing the outer ends of said cross bar to said side bars, a hydraulic cylinder between said pair of bars, means securing said cylinder relative to said pair of bars, a plunger slidably in said cylinder, a pulley carried by the forward end of said plunger, a second pulley dependingly disposed below said cylinder rearwardly of said first named pulley, a third pulley carried by said sweep structure, slide means carried by said plunger and slidably engaging under said horizontal flanges for relieving said plunger of vertical loads, and a cable fixed at one end relative to said plunger and trained about said pulleys and having the other end fixed to the top of said support.

2. A sweep operator attachment for a stacker and loader having a base frame formed of side

bars and transverse connecting bars, an upstanding support carried by said base frame, and a rockable sweep structure rockably mounted intermediate the height of said support; said attachment comprising a frame formed of a pair of parallel frame bars for disposing lengthwise of said base frame and at a forward and upward inclination relative to the latter, said frame bars being each formed with an inwardly extending flange along the top edge thereof, means securing the forward portions of said pair of bars to a forward connecting bar, a cross bar fixed to the rear portions of said pair of bars, means securing the outer ends of said cross bar to said side bars, a hydraulic cylinder between said pair of bars, means securing said cylinder relative to said pair of bars, a plunger slidably in said cylinder, a pulley carried by the forward end of said plunger, a second pulley dependingly disposed below said cylinder rearwardly of said first named pulley, a third pulley carried by said sweep structure, a cable fixed at one end relative to said plunger and trained about said pulleys and having the other end fixed to the top of said support, and slide means carried by said plunger slidably engaging under said flanges formed on said pair of bars.

3. A sweep operator attachment for a stacker and loader having a base frame formed of side bars and transverse connecting bars, an upstanding support carried by said base frame, and a rockable sweep structure rockably mounted intermediate the height of said support; said attachment comprising a frame formed of a pair of parallel bars for disposing lengthwise of said base frame and at a forward and upward inclination relative to the latter, said bars each being formed with an inwardly directed flange along the top edge thereof, means securing the forward portions of said pair of bars in overlying position on one of said connecting bars, a cross bar fixed relative to the rear portions of said pair of bars, means securing the outer ends of said cross bar to said side bars, a pair of plates fixed between said pair of bars, a hydraulic cylinder disposed on said plates between said pair of bars, means securing said cylinder on said plates, a plunger slidably in said cylinder, a pulley carried by the forward end of said plunger, a pulley dependingly carried by one of said plates, a pulley carried by said sweep structure, slide means carried by said plunger and engaging slidably under said flanges on said bars, and a cable fixed at one end to said plunger and trained about said pulleys and having the other end fixed to the top of

4. A sweep operator attachment for a stacker and loader having a base frame formed of side bars and transverse connecting bars, an upstanding support carried by said base frame, and a rockable sweep structure rockably mounted intermediate the height of said support; said attachment comprising a frame formed of a pair of parallel bars for disposing lengthwise of said base frame and formed with inwardly directed flanges along the top edge thereof, means securing the forward portions of said pair of bars in overlying position on one of said connecting bars, a cross bar fixed relative to the rear portions of said pair of bars, means fixed between said cross bar and said pair of bars supporting the latter in downwardly spaced relation with respect to said cross bar whereby said parallel bars are upwardly and forwardly inclined relative to said base frame, means securing the outer ends of said

cross bar to said side bars, a pair of plates fixed between said pair of bars, a hydraulic cylinder disposed on said plates between said pair of bars, means securing said cylinder on said plates, a plunger slidable in said cylinder, a pulley carried by the forward end of said plunger, a pulley dependingly carried by one of said plates, a pulley carried by said sweep structure, slide means carried by said plunger and slidably engaging under said flanges, and a cable fixed at one end to said plunger and trained about said pulleys and having the other end fixed to the top of said support.

WILLIAM V. WARREN.
